SATURATING KETTLE

Joseph Francis Dillon, Philadelphia, Pa., assignor
to The Barrett Company, New York, N. Y., a
corporation of New Jersey

Application August 26, 1933, Serial No. 686,950

4 Claims. (Cl. 91—46)

This invention relates to saturators and more particularly to saturating kettles for impregnating absorbent fibrous sheet materials, such as roofing felt, with liquid saturant such as asphalt, 5 coal tar, or coal tar pitch.

One object of this invention is to provide a kettle roll for saturating kettles which offers improved traction and support for the sheet material being saturated.

10 Another object of this invention is to provide an improved apparatus for impregnating absorbent sheet material with hot saturant in which weaving of the sheet during its passage through the apparatus is effectively prevented.

15 Another object of this invention is to provide a kettle for saturating sheet roofing with hot bituminous material in which special kettle rolls are provided. These rolls are designed to remove foam and excess saturant from the surface 20 of the sheet, thereby preventing lateral floating or slippage of the sheet during its passage over the rolls.

25 Other objects and advantages will appear from the following detailed description of my invention.

It is common practice at the present time to 30 saturate absorbent fibrous sheet material, such as sheet roofing felt, by passing the sheet material several times in and out of a bath of hot saturant contained in a suitable tank or kettle. This is done by looping the sheet over a plurality 35 of kettle rolls or guide rolls disposed above and below the surface of the saturant in the tank. Contact of the hot saturant with the sheet, however, causes moisture, which is generally present in the sheet, to vaporize and form steam. The steam and other gases present in the sheet which have been driven out by the hot saturant, combine with the saturant to produce a foam or 40 froth on the surface of the sheet and on the surface of the kettle rolls. This foam forms an anti-friction film on the surface of the kettle roll and sheet which prevents actual contact of the sheet with portions of the kettle rolls, especially 45 the kettle rolls above the surface of the saturant in the tank. Hence, as the sheet passes through the saturator it frequently floats laterally or side slips during its passage over the kettle rolls. Slipping or weaving of the sheet causes an even 50 tension on one side of the sheet and often results in ruptures or breaks during passage of the sheet through the kettle.

In the copending application of J. Pearl, Serial No. 686,947, filed on even date herewith there is disclosed saturating equipment designed to re-

move the film of foam and excess saturant from the surface of the sheet and give improved traction between the sheet and the kettle rolls. My invention is an improvement on the apparatus invention of this application. In accordance with my invention, the saturating kettle is provided with rolls having a series of raised and depressed areas thereon, the raised areas being arranged to contact with the sheet, and the depressed portions permitting foam and excess 10 saturant to drain thereinto and thus be removed from the sheet and the raised portions of the roll contacting with the sheet. The rolls may be cast integrally or built up in the shape of fluted or corrugated rolls. If desired, such a 15 roll may be made from the customary smooth-surfaced cylindrical roll merely by fixing a plurality of angle irons longitudinally along its periphery. I have found that such rolls are ideal for guiding the sheet through the saturating tank 20 since the comparatively deep grooves or depressed portions of the flutes permit the escape of excess saturant and foam from the surface of the sheet, while the raised portions serve to support the sheet and give improved traction between 25 the sheet and the roll.

For a better understanding of the invention reference should be made to the accompanying drawing wherein is shown, by way of illustration, a preferred embodiment of this invention, and in 30 which:

Fig. 1 is a side elevation of a saturating apparatus embodying this invention, the saturating tank being shown in section.

Fig. 2 is an enlarged view partly in section, 35 showing a kettle roll constructed in accordance with this invention;

Fig. 3 is a sectional view taken along the line 3—3 of Fig. 2.

Referring to the drawing with particular reference to Fig. 1, numeral 2 indicates an absorbent fibrous sheet, such as the usual roofing felt, passing over a guide roll 4 into a saturating kettle indicated generally by the reference numeral 6. This kettle may comprise the usual rectangular 45 tank 8 made of sheet steel or other suitable material and adapted to hold cementitious waterproofing composition, such as heated asphalt or other fluid bituminous material, utilized for the impregnation and saturation of roofing felts. 50

In a manner well known in the art, the saturating tank 8 is provided with a series of lower kettle rolls or guide rolls 10—10 and a set of upper kettle rolls or guide rolls 12—12. Rolls 10, of which there may be any desired number, are arranged in a 55

spaced horizontal row near the bottom of the tank 8 so that in operation they will be a considerable distance below the level of the saturant in the tank indicated by line 14. These rolls may be the ordinary smooth-surfaced cylindrical type fixed on freely-rotatable shafts 16 mounted in suitable bearings.

Upper kettle rolls 12 are arranged in a horizontal row near the top of the tank in staggered relation to the lower kettle rolls 10, and are set on freely rotatable shafts 17 mounted in suitable bearings. These rolls are preferably a considerable distance above the surface 14 of the saturant in the tank. The upper kettle rolls 12 in accordance with my invention, as hereinafter pointed out, are designed and constructed to prevent weaving or slipping of the sheet passing thereover.

Numerals 18 and 19 denote a pair of squeeze rolls which may be driven at any desirable speed by a suitable drive (not shown). These rolls draw the fibrous sheet 2 from the source of supply through the saturating tank, and squeeze excess saturant from the sheet as it passes between them.

Although four upper kettle rolls 12 are shown in Fig. 1 of the drawing, only one will be described in details since all the rolls 12 shown on the drawing are of like construction.

As shown in Figs. 2 and 3, each roll 12 comprises a hollow cylindrical shaped shell 22 provided around its periphery with a plurality of parallel flutes 24 extending longitudinally of the shell. These flutes may be constructed by welding, riveting, or otherwise securing a series of angle irons 26 of any suitable size to the peripheral surface of the shell. I have found that $\frac{1}{2}''$ x $\frac{1}{2}''$ angle irons, of a length equal to that of the shell, are a desirable size and may advantageously be used by welding to the shell so that the $\frac{1}{2}''$ legs extend radially therefrom. As shown in Fig. 3, one leg of each angle iron is welded to the shell so that a small clearance is provided between it and the radially extending leg of a contiguous iron. Thus, relatively closely spaced raised portions are provided about the circumferential surface of the shell 22, each raised portion extending across the length of the shell. The hollow shell 22 may be fixed to the shaft 17, passing axially therethrough, by means of disc-shaped supports 28 fitted into the ends of the shell and suitably secured to the interior of the shell and the shaft 17.

The operation of the apparatus is as follows:

A sheet of absorbent fibrous material, which may be the usual roofing felt made of rag fiber, paper stock, or other fibrous material, with or without suitable fillers, as well known in the art, is led from the usual paper making machine or other source of supply over feed roll 4 into the saturating kettle 6 containing a bath of molten hot asphalt or other saturant, which is maintained in a molten condition by suitable heating means such as a steam coil associated with the kettle 6. As soon as the absorbent sheet is immersed in the saturating bath, the hot saturant begins to enter the pores of the sheet.

Moisture contained in the sheet is vaporized, the steam thus formed being expelled from the sheet, and, together with the air leaving the sheet, causing the formation of foam in the bath and on the surface of the sheet.

After passing under the first lower kettle roll 10, the partly impregnated sheet is led out of the bath and looped over the first upper kettle roll 12. As the sheet contacts with upper roll 12, the foam, steam, oily vapors, and excess saturant adhering to the sheet, leave the sheet and pass into the deep

flutes or depressed portions of the roll. The steam and oily vapors escape therefrom to the atmosphere while the liquid portions of the foam and excess saturant drain from the ends of the roll back into the saturating kettle.

The removal of these film forming materials from the surface of the sheet permits intimate contact between the sheet and the roll thereby preventing slippage between the two which has heretofore resulted in weaving and often rupture of the sheet. Furthermore, the flexible sheet, wet with liquid saturant, tends to cling to the raised portions of the roll, i. e., the tops of the flutes, so that satisfactory traction is obtained between the sheet and the roll.

After passing over the first upper roll 12 in the series, the partly impregnated sheet is led back into the bath and passed alternately under each of the remainder of lower kettle roll 10 and over each of the upper kettle rolls 12 in a series of loops. In this way the sheet is alternately immersed in the hot saturant and exposed to the atmosphere until the impregnation is complete. The completely saturated sheet is withdrawn from the saturating tank and passed through squeeze rolls 18 and 19. These rolls, which may be driven at any desirable speed, not only pull the sheet from the source of supply over the kettle rolls in the saturating tank, but also press excess saturant from the saturated sheet and allow it to drain back into the saturating tank.

After passing through the squeeze rolls the saturated sheet may be sent through a looping device (not shown) to allow the saturant to cool and to thoroughly impregnate the fibrous sheet. The dried impregnated material may be used as a waterproof covering or may be further treated to form coated and surfaced roofing elements or sheet roofing in a manner well known in the roofing art.

It will be noted that the saturating kettle and kettle rolls of this invention are simple in design and construction. The improved kettle rolls destroy the cushioning effect of foam and excess saturant on the sheet being saturated and provide improved traction or contact between the sheet and the rolls. As has been pointed out, a considerable economy is effected by this invention since the operation requires less labor and supervision than has heretofore been necessary and eliminates delays for repairs or adjustments. Furthermore, loss of material through breakage or rupture of the sheet is minimized if not entirely eliminated.

Although, as described above, all of the upper kettle rolls are preferably constructed in accordance with this invention, it should be understood that only one or more of the rolls may be so constructed.

Similarly, the fluted or corrugated rolls of this invention may be employed advantageously in the lower series as well as in the upper series.

It is intended that all matter contained in the above description or shown in the accompanying drawing, shall be interpreted as illustrative and not in a limiting sense.

I claim:

1. In apparatus for saturating absorbent sheet material with liquid saturant, the combination comprising a tank for holding the saturant, a series of rotatable rolls positioned below the surface of the saturant in the tank, a kettle roll positioned above the surface of the saturant, the sheet passing successively under a roll of said series and over said kettle roll and again under

5 a roll of said series whereby it is repeatedly immersed in and withdrawn from said saturant, said kettle roll being provided with a series of raised portions spaced therearound to drain excess saturant and foam from the sheet between immersions thereof.

2. In apparatus for saturating absorbent sheet material with fluid bituminous material, the combination comprising a tank for holding the 10 bituminous material, a series of rotatable rolls positioned below the surface of the bituminous material in the tank, a second series of rolls positioned above the surface of the bituminous material, the sheet passing alternately under the 15 rolls of said first series and over the rolls of said second series whereby it is repeatedly immersed in and withdrawn from said bituminous material, the rolls of said second series having a plurality of angle irons attached thereto and 20 extending generally parallel to the longitudinal axis of the rolls, said angle irons forming drains for draining excess saturant and foam from said sheet between immersions.

3. In apparatus for saturating sheet roofing 25 felt with hot fluid bituminous material comprising a tank for holding the bituminous material, a series of rotatable cylindrical rolls positioned below the surface of the bituminous material in the tank, a second series of rotatable cylindrical

rolls positioned above the surface of the bituminous material, the felt sheet during the saturating operation passing alternately under the rolls of said first series and over the rolls of said second series whereby it is repeatedly immersed 5 in and withdrawn from the bituminous material in the tank, the rolls of said second series being provided with a plurality of angle irons attached thereto and projecting therefrom, said angle irons being substantially parallel to each other 10 and to the longitudinal axis of the rolls and forming therebetween drains for draining excess bituminous material and foam from said sheet between successive immersions of the same.

4. In apparatus for saturating absorbent sheet 15 material, the combination comprising a tank containing liquid saturant, means within the tank below the surface of the saturating material for guiding the sheet material therethrough and a roll provided with spaced raised portions 20 on the surface thereof, said roll being positioned so that sheet material to be saturated passes first over said roll and then into said saturant and under the guiding means positioned below the surface of the saturant, said roll preventing 25 weaving and sideslipping of the sheet material as it passes into and through the saturant.

JOSEPH FRANCIS DILLON.
